Charles A. ODDO.

By *Clarence A. O'Brien* Attorney

UNITED STATES PATENT OFFICE.

CHARLES A. ODDO, OF BUFFALO, NEW YORK.

BRUSH KIT.

Application filed April 15, 1927. Serial No. 184,095.

The present invention relates to improvements in special receptacles and has reference more particularly to a kit for paint or varnish brushes.

- 5 One of the important objects of the present invention is to provide a kit of the above mentioned character which is adapted to receive a number of paint or varnish brushes and support the same within the kit in such 10 a manner as to enable a person to readily and easily remove any desired brush from the kit without interfering with the other brushes, thus saving considerable time and labor.
- 15 A further object of the invention is to provide a kit for paint or varnish brushes wherein the kit may be filled with a liquid such as benzine, gasoline, or the like for keeping the bristles of the brushes in a 20 moist condition when not in use, additional means being provided whereby the liquid may drain off from the bristles into the receptacle or kit when the brush carrying unit is raised upwardly out of the kit in order 25 that any particular brush may be removed from the kit.

A still further and important object is to provide a kit of the above mentioned character wherein the brush carrying unit 30 is of such construction as to automatically move to an open position when the unit is raised a predetermined distance in the kit so that the brushes will be readily visible and the desired brush can be readily re- 35 moved from the unit.

A still further object is to provide a brush kit of the above mentioned character which is simple in construction, inexpensive, strong and durable and further well adapted to the 40 purposes for which it is designed.

Other objects and advantages of the invention will become apparent during the course of the following description.

In the accompanying drawings forming a 45 part of this application, and in which like numerals indicate like parts throughout the same:

Figure 1 is a side elevation of the kit embodying my invention, a part of the receptacle being broken away to more clearly disclose the arrangement of the tray and the brush carrying unit in the receptacle.

Figure 2 is a vertical sectional view taken 50 approximately on the line 2—2 of Figure 1, 55 showing a construction of one of the arms at the ends of the tray.

Figure 3 is a vertical sectional view taken approximately on the line 3—3 of Figure 1.

Figure 4 is a longitudinal sectional view 60 through the kit or disclosing in top plan the two brush carrying units arranged therein.

Figure 5 is a vertical sectional view 65 through one of the brush carrying units for disclosing the manner in which a brush is positioned therein, and

Figure 6 is a detail perspective view of 70 one of the brush carrying units, showing the same in its open position.

In the drawings wherein for the purpose 75 of illustration is shown the preferred embodiment of my invention, the numeral 1 designates generally my improved brush kit, the same comprising the substantially rectangular shaped receptacle 2 which is open at its top. A hinged cover 3 is provided 80 for the open top of the receptacle and this cover is hinged at its rear side to the rear side of the upper portion of the receptacle as at 4. Any suitable locking means such as is shown generally at 5 is associated with 85 the front side of the cover and the adjacent side of the upper portion of the receptacle whereby the cover will be locked in a closed position on the open top of the receptacle. A suitable handle 6 is attached to the top 90 of the cover to provide means whereby the kit may be easily carried. The kit is preferably constructed of galvanized sheet metal, although it is to be understood that I do not wish to limit myself to the particular material from which the kit may be constructed.

Adapted to be removably arranged within 95 the receptacle 2 is the elongated tray 7, the same being formed with a series of drain openings 8, as is clearly disclosed in Figures 1 and 3. Extending upwardly from each 100 end of the tray is the relatively wide arm 9, the side edges of which are flanged outwardly as illustrated at 10. The arms 9 are of a length substantially equal to the length of the end walls of the receptacle and are of a width slightly less than the width of the receptacle 2. The tray 7 is of a length slightly less than the length of the receptacle and this is clearly disclosed in Figures 105 1, 2, 3, and 4, of the drawings. For the purpose of spacing the ends of the tray with respect to the end walls of the receptacle, I provide spacing members 11 which extend outwardly from the upstanding arms 9 adjacent the upper ends thereof.

Each upstanding arm 9 is formed with

a pair of parallel spaced longitudinally extending slots indicated by the numeral 12, and the purpose of these slots will be hereinafter more fully described.

5 A brace rod 13 extends between the upper portions of the vertical arms 9 and this is clearly shown in the drawings.

The brush kit further includes the provision of a pair of brush carrying units designated generally by the numeral 14. Each 10 unit comprises a casing including a pair of complementary sections 15 and 16, respectively. Each section is preferably constructed from a sheet metal plate which is curved 15 in such a manner whereby the sides of the casing gradually converge toward the bottom, as is readily obvious from the construction shown in Figure 5. The lower edge of the inner plate like section 15 is rolled as 20 illustrated at 17 for a purpose to be presently apparent. The upper edges of the plate like sections are bent back upon themselves to form smooth upper edges. Extending inwardly from the outer plate-like 25 section at the ends and the intermediate portion thereof are the vertical parallel spaced partition members 18 and the inner plate-like section 15 is formed with vertical slots 19 to accommodate these partitions or separators 18 in the manner clearly shown in 30 Figure 6.

An elongated rod 20 extends through the lower rolled edge portion 17 on the inner plate section 15 and through registering 35 openings provided in the lower ends of the several partitions or separators 18 whereby a hinge connection is provided between the lower longitudinal edges of the plate-like sections comprising the casing of each of the brush carrying units 14. The endmost portions provide a closure for the ends of the casing when the sections are brought together and when said sections are disposed in a vertical position, the outer free edges of 40 the partitions or separators will project through the respective slots 19 provided therefor in the inner plate 15 whereby a plurality of brush receiving compartments will be formed in each casing and the partitions 45 and slots are so arranged as to form compartments of various sizes in order to accommodate paint or varnish brushes of different sizes.

An elongated handle 21 extends upwardly 55 from the innermost plate-like section 15 at the intermediate portion thereof and this handle provides a means whereby each brush carrying unit 14 may be raised or lowered in the receptacle 2 in the manner to be 60 presently described.

The rod 20 has its ends projecting beyond the ends of the sections comprising the casing of each brush carrying unit and the outwardly projecting ends of the rods 20 are 65 adapted for slidable disposition within the

respective aligned slots 12 provided therefor in the upstanding arms 9 formed at the ends of the tray 7. The pins cooperate with the slots in guiding the brush carrying units during their vertical slidable movement 70 within the receptacle and normally the outwardly projecting ends of the rods are disposed in the lowermost ends of the slots and the brush carrying units will rest on the tray 7. 75

The inner plate-like section 15 is formed with a series of drain openings 22 adjacent the lower edge thereof while a similar series of drain openings are arranged in the lower portion of the complementary plate-like section 16 as is indicated by the numeral 23. 80

The kit is of such size as to accommodate two brush carrying units and the units are arranged as shown in Figure 3 so that the handles 21 extend upwardly on opposite 85 sides of the brace rod 13.

The receptacle is to be partially filled with any suitable liquid such as benzine, gasoline, or the like, which liquid tends to keep the bristles of the brushes moist and soft and by 90 reason of the openings in the complementary sections of each of the casings of the brush carrying units the bristles will be immersed in the liquid when the brush carrying units are in their lowermost positions in the receptacle. In this manner, the brushes will 95 be kept in individual compartments, and the liquid cannot leak out of the receptacle and when the cover is in a closed position on the open top of the receptacle, dust or other foreign matter cannot enter the receptacle.

In this manner, the brushes will be kept in proper condition for use whenever necessary and it will not be necessary to wrap 100 the individual brush up in a piece of paper or the like such as is now commonly done.

In order to obtain access to the brushes, the cover 3 is swung to an open position and the handle 21 of either unit or both units 110 is grasped and lifted upwardly so as to cause the casing or casings to be raised upwardly and during such movement, the pins 20 will slide upwardly in the slot when both the units are lifted. As soon as the outer section 16 reaches a predetermined point, during the upward sliding movement of the brush carrying unit, the same will swing outwardly on the pivot formed by the rod 20 so that said plate-like section 120 will rest against the outer edge of the upper open end of the receptacle and the brushes will also be tilted whereby a person may readily view the several brushes arranged in the respective compartments formed by 125 the partitions 18 and the complementary slots 19 and the desired brush may be readily removed from its compartment. It is of course to be understood that during the upward movement of the brush carrying unit 130

in the receptacle, the liquid will drain from the bristles and will drop into the bottom of the receptacle.

When the handle or handles are released 5 the brush carrying units will by gravity return to their normal positions in the bottom of the receptacle 2.

Whenever it becomes necessary to clean out the receptacle, the tray can be readily 10 moved therefrom by grasping the upper ends of the arms and lifting the same bodily out of the open upper end of the receptacle in an obvious manner.

It will thus be seen from the foregoing 15 description, that I have provided a kit for paint and varnish brushes which will at all times maintain the bristles of the brushes in a moist and soft condition, and furthermore by constructing a brush carrying unit 20 in the manner as above described and as further shown in the drawings, a number of brushes can be neatly arranged in such a manner as to enable a person to readily remove any particular brush without having 25 to examine the entire number of brushes.

The simplicity of my device enables the 30 same to be constructed at a very low cost and furthermore will at all times be positive and efficient in carrying out the purposes for which it is designed.

While I have shown the preferred embodiment of my invention, it is to be understood that various changes in the size, shape and arrangement of parts may be resorted to, 35 without departing from the spirit of the invention and the scope of the appended claims.

Having thus described the invention, what I claim is:—

40 1. In a kit for brushes, an open top receptacle, a cover therefor, a brush carrying unit vertically slidable in the receptacle, a handle associated with the unit for lifting the same upwardly to permit the ready removal of a brush when the cover for the receptacle is opened, said unit comprising a casing including complementary sections hingedly connected together at their lower edges, said sections being automatically separated when the unit is raised upwardly a predetermined distance in the receptacle.

45 2. In a kit for brushes, an open top receptacle, a cover therefor, a brush carrying unit vertically slidable in the receptacle, a handle associated with the unit for lifting the same 50 upwardly to permit the ready removal of a

brush when the cover for the receptacle is opened, said unit comprising a casing including complementary sections hingedly connected together at their lower edges, said sections being automatically separated when the unit is raised upwardly a predetermined distance in the receptacle, and partitions arranged on the inner face of one of the sections for dividing the casing into a plurality of brush receiving compartments. 60

3. In a kit for brushes, an open top receptacle, a cover therefor, a brush carrying unit vertically slidable in the receptacle, a handle associated with the unit for lifting the same 70 upwardly to permit the ready removal of a brush when the cover for the receptacle is opened, said unit comprising a casing including complementary sections hingedly connected together at their lower edges, said sections being automatically separated when the unit is raised upwardly a predetermined distance in the receptacle, and partitions arranged on the inner face of one of the sections for dividing the casing into a plurality of brush receiving compartments, the 75 other section being formed with slots to accommodate the free edges of the partitions. 80

4. In a kit for brushes, an open top receptacle, a cover therefor, a removable tray arranged within the bottom of the receptacle, arms extending upwardly from the ends of the tray, a brush carrying unit, cooperating means between the unit and said arms whereby said unit may be moved vertically 90 between the arms, and a handle associated with the unit for actuating the same. 85

5. In a kit for brushes, an open top receptacle, a cover therefor, a removable tray arranged within the bottom of the receptacle, arms extending upwardly from the ends of the tray, a brush carrying unit, cooperating means between the unit and said arms whereby said unit may be moved vertically between the arms, a handle associated with the unit for actuating the same, said unit comprising a casing including complementary sections hingedly connected together at their lower edges, each section being provided with drain openings in the lower portion thereof, the sections adapted to be automatically separated when the unit is raised upwardly a predetermined distance in the receptacle. 100 105

In testimony whereof I affix my signature.

CHARLES A. ODDO.
